UNITED STATES PATENT OFFICE.

EDWARD L. ADREON, JR., OF ST. LOUIS, MISSOURI, ASSIGNOR TO
AMERICAN BRAKE SHOE & FOUNDRY COMPANY, OF JERSEY
CITY, NEW JERSEY, A CORPORATION OF NEW JERSEY.

INTERCHANGEABLE AND REVERSIBLE BRAKE-SHOE HEAD.

SPECIFICATION forming part of Letters Patent No. 791,854, dated June 6, 1905.

Application filed April 7, 1903. Renewed January 23, 1905. Serial No. 242,300.

To all whom it may concern:

Be it known that I, EDWARD L. ADREON, Jr., a citizen of the United States, residing at St. Louis, State of Missouri, have invented certain new and useful Improvements in Interchangeable and Reversible Brake-Shoe Heads, of which the following is a specification, containing a full, clear, and exact description, reference being had to the accompanying drawings, forming a part hereof.

My invention relates to improvements in interchangeable and reversible brake-shoe heads; and it consists of the novel construction, combination, and arrangement of parts hereinafter shown, described, and claimed.

The object of my invention is to construct a brake-shoe head to which is adapted to be applied to any of the well-known types of brake-shoes now on the market. The prevailing types of brake-shoes now on the market are commercially known as the "American Brake Company's" type of shoe and the "Christy" type of shoe.

To show the utility of my invention in a commercial sense, it is only necessary to state that, for instance, if a railroad has a brake-shoe head especially constructed to take one of the above types of brake-shoes it would not be possible to use with said brake-shoe head the other type of brake-shoe.

The object of my invention is really to make a brake-shoe head to which any of the well-known commercial types of brake-shoes may be applied.

In the drawings, Figure 1 is a side elevation, with parts broken away, of my improved brake-shoe head. Fig. 2 is a top plan view. Fig. 3 is a perspective view of what is commercially known as the "American Brake Company's" type of brake-shoe. Fig. 4 is a perspective view of what is commercially known as the "Christy" type of brake-shoe. Fig. 5 is a perspective view of a modified form of what is commercially known as the "Christy" type of brake-shoe.

Heretofore brake-shoe heads have been constructed with a central opening to receive the

central connecting-lug of the brake-shoe, as illustrated in Figs. 4 and 5. Also the brake-shoe head, as has heretofore been manufactured, provided with one aperture or hole in one end to receive the type of brake-shoe illustrated in Fig. 3 is old; but the idea of making a brake-head with a central aperture to receive a brake-shoe provided with a central connecting-lug and also to have the same brake-shoe head provided with an additional aperture in its end or in both of its ends to receive a type of brake-shoe provided with a hole in its terminal portion is new, so far as I am informed, and constructing a brake-shoe head with a central aperture and with a hole in each of its ends to make the same reversible is also new.

Referring to the drawings, 1 indicates my brake-shoe head, which is provided in its central portion with a hole 2 and is provided at its end portions with holes 3 and 4.

5 indicates what is commercially known as the "Christy" type of brake-shoe. Said 70
brake-shoe is provided at its central portion with an integral lug 6, and said lug 6 is provided with a transverse hole or opening 7. Said brake-shoe is applied to the brake-shoe head 1 by means of a locking-pin 8.

9 indicates what is commercially known as the "American Brake Company's" type of brake-shoe. Said brake-shoe 9 is provided with a hole 10, and when it is desired to apply said brake-shoe to my brake-shoe head 1 it is 80
only necessary to use a brake-shoe key-bolt and pass the same through the opening 10 and either of the openings 3 and 4, formed in the brake-shoe head 1.

My brake-shoe head 1 is also provided with 85
cut-away portions 11, the object of these cut-away portions 11 being to permit my brake-shoe head to receive a modified type of what is commercially known as the "Christy" type of brake-shoe, which type is illustrated in Fig. 90
5 and which is indicated by 12. The modified form of what is known as the "Christy" type of brake-shoe has the usual integral connecting-lug 6 and is also provided at its end portions

with lugs 13, which are adapted to be located in the cut-away portions 11 of my brake-shoe head.

- It will be seen from the foregoing description that by constructing a brake-shoe head with a central aperture and with an aperture or hole at each end and with the cut-away portions 11 I have constructed or devised a brake-shoe head which is reversible and which is adapted to receive the commercial types of brake-shoes now on the market. In other words, if a railway company is provided with my brake-shoe heads and they desire to change their type of brake-shoes they may still retain their brake-shoe heads, to which may be fitted any of the brake-shoes now on the market.
- Having fully described my invention, what I claim as new, and desire to have secured to me by the grant of Letters Patent, is—
1. An interchangeable brake-shoe head provided with a central opening adapted to receive the fastening-lug of a brake-shoe and an open-

ing at one end adapted to receive a brake-shoe key-bolt, substantially as specified.

2. An interchangeable and reversible brake-shoe head provided with a central opening adapted to receive the fastening-lug of a brake-shoe and an opening at each end adapted to receive a brake-shoe key-bolt, substantially as specified.

3. An interchangeable and reversible brake-shoe head provided with a central opening 2 adapted to receive the fastening-lug of a brake-shoe and openings 3 and 4 formed in its end portions adapted to receive a brake-shoe key-bolt, and cut-away portions 11, substantially as specified.

In testimony whereof I have signed my name to this specification in presence of two subscribing witnesses.

EDWARD L. ADREON, JR.
